UNITED STATES PATENT OFFICE.

RALPH APPLEBOM AND JOE SIDENBITEL, OF DALLAS, TEXAS.

FASTENER.

SPECIFICATION forming part of Letters Patent No. 670,655, dated March 26, 1901.

Application filed July 31, 1900. Serial No. 25,400. (No model.)

To all whom it may concern:

Be it known that we, RALPH APPLEBOM and JOE SIDENBITEL, citizens of the United States, and residents of Dallas, in the county of Dallas and State of Texas, have invented a new and Improved Fastener, of which the following is a full, clear, and exact description.

The invention relates to fasteners for holding shield bows, ties, scarfs, and other similar articles of wearing-apparel in position, also belts, suspenders, valises, trunks, blinds, garters, gloves, skirts, portières, drop-curtains, umbrellas, coats, caps, pocket-books, corsets, leggings, doors, &c.; and its object is to provide a new and improved fastener which is simple and durable in construction, easily applied to the article, and conveniently attached to or detached from a collar-button or like device.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a rear face view of a shield-bow provided with the improvement. Fig. 2 is a transverse section of the same. Fig. 3 is a face view of the improvement as applied to a collar-button, the latter being shown in section. Fig. 4 is a transverse section of the same with the collar-button shown in elevation; and Fig. 5 is a sectional plan view of the improvement as applied, the section being on the line 5 5 in Fig. 3.

The improved fastener is provided with a metallic attaching-plate A, approximately rectangular in shape and formed at the corners with angular prongs A', adapted to engage and be clenched on the article B to be held in position on a collar-button C or like device. The attaching-plate A is formed at or near its middle with a recess A² for the reception of the head C' of the collar-button, as is plainly shown in Fig. 4, one end of said head C' extending under a cross-bar D, forming an integral part of the attaching-plate and extending over one end of the recess A², to abut against the rear face of the head C' at one

end thereof, as is plainly indicated in Fig. 4. The other end of the head C' is adapted to be engaged by a slide E, in the form of a rectangular plate mounted to slide in bearings or guideways A³, integrally formed on the sides of the attaching-plate A. The sliding movement of the slide E is limited by the cross-bar D, previously mentioned, the latter extending for the purpose into an elongated opening E', formed in the slide E, as is plainly shown in Fig. 3.

When it is desired to secure a shield-bow B in position on the collar-button, then the operator first moves the slide E into an open position, so that the opening E' of the slide fully registers with the recess A² in the attaching-plate, as indicated in Fig. 1. When the slide is in this position, the device can be readily placed upon the head of the collar-button by seating the head C' in the recess A², as is plainly shown in Fig. 4, one end of the said head C' extending under the fixed cross-bar D. The operator now imparts a downward sliding movement to the slide E until the shoulders E² of said slide abut against the cross-bar D, as is plainly shown in Fig. 3, said slide now passing over the rear face of the other end of the head C' of the collar-button to securely lock the latter in position in the recess A². (See Figs. 3 and 4.) From the foregoing it is evident that when the several parts are in this position the fastener is securely locked in position on the collar-button, and as the fastener is rigidly attached to the bow or other article it is evident that the said bow or other article is securely held in position for the time being.

When it is desired to detach the bow or other article, then the operator simply slides the slide E upward to disengage the slide from the head C', and then the attaching-plate can be slipped off the head C' to disconnect the whole device from the collar-button.

Having thus fully described our invention, we claim as new and desire to secure by Letters Patent—

1. A fastener, comprising an attaching-plate having a recess for the reception of the head of a collar-button, a cross-bar extending over one end of said recess to form an abutment for one end of said button-head, and a locking-slide movable on said attaching-plate

and having an elongated opening adapted to register with said recess, the said slide being adapted to engage the other end of the head of the collar-button, the said cross-bar on the 5 attaching-plate extending into the said opening in the slide to limit the movement of the slide, as set forth.

2. A fastener, comprising an attaching-plate provided with means for attachment to 10 a shield-bow or like article, said plate having at or near its middle a recess for the reception of the head of a collar-button, a cross-bar extending over the lower end of said recess to form an abutment for one end of said 15 button-head, and a locking-slide mounted to slide in guideways on said attaching-plate and having an elongated aperture adapted to

register with said recess, said aperture having an enlarged portion forming shoulders on the slide, the said slide being adapted to engage the outer end of the collar-button, said cross-bar extending into the enlarged portion of the opening in the slide and forming a stop for said locking-slide to limit the opening and closing movement thereof, as set forth.

In testimony whereof we have signed our names to this specification in the presence of two subscribing witnesses.

RALPH APPLEBOM.
JOE SIDENBITEL.
